COAT

Maurice Paley, New York, N. Y.

Application March 20, 1947, Serial No. 736,061

2 Claims. (Cl. 2--97)

1

The present invention is concerned with double duty outer coats and more especially with ladies' coats of the type comprising an inner coat readily removable from the combined garment to adapt the same for wear in more temperate weather.

As conducive to a clear understanding of the invention, it is noted that in order to avoid undue bulk in winter wear it is desirable that the inner coat be fitted rather snugly at its edge to the border of the inturned facing of the outer coat. With such snug fit, however, the coat in wear serves in a manner of speaking, as a strait-jacket, since it affords inadequate freedom of arm and shoulder movement.

It is among the objects of the invention to provide a garment of the above type which will present no excessive bulk or lumpiness and will give no conspicuous evidence of the double thickness of coat as worn in winter, which lends itself to embodiment in any of a variety of styles, even in the plain, tailored, unpleated body-fitting type of coat, and yet affords complete freedom of arm and shoulder movement without excessive strain on the seams or fabric, and which, after accommodating vigorous arm and shoulder movement of the wearer, will show no disarray as a consequence of such movement but inherently maintains its well-groomed appearance.

In the accompanying drawings in which is shown one of various possible embodiments of the several features of the invention,

Fig. 1 is a perspective view showing the composite coat for winter wear with the wearer manipulating the hookless fastener.

Fig. 2 is a perspective view of the front of the inner coat member.

Fig. 3 is a view similar to Fig. 2, showing a rear view of said inner coat member.

Fig. 4 is a view on a greatly enlarged scale of the inner upper area of the inner coat body, as shown in Fig. 2,

Fig. 5 is a transverse sectional view taken along line 5--5 of Fig. 4 and on a still larger scale and

Fig. 6 is a fragmentary view on a larger scale taken on line 6--6 of Fig. 1.

Referring now to the drawings, the double duty coat is of the general type comprising an outer coat 10 and an inner coat 11 both preferably of wool or the like. The outer coat preferably has a lining 12 of silk, rayon, mohair, or like coat lining material, which lining is attached to the edge of a wide inturned facing 13 of the main wool fabric, extending along the sides and connecting collar portion of the coat. The inner coat 11 is of wool at its inner or body engaging face 14 and preferably has an outer portion 15 of lining material similar to lining 12. Preferably the inner

2

coat has no collar but has sleeves 16 desirably with cuffed wrist ends 17. The width of the inner coat is preferably substantially equal to the span between the inturned facing portions 13 of the outer coat, so that when the inner coat is removably attached to said facing portions it will span snugly therebetween without folds or lumping due to extra material. Desirably the attachment is by hookless fastener means. One slide fastener chain 18 is on the outer coat and extends along the entire border of the facing 13 and is preferably concealed below a welt strip 19 at the edge of said facing. The complementary slide fastener chain 20 of the inner coat extends along the entire length of its inner edge. Thus when the two coats are assembled for winter wear, the inner coat spans snugly between the lateral facing lengths along the inner face of the outer coat; the sleeves 16 of the inner coat will embrace the wrist of the wearer with the sleeves 21 of the outer coat extending in normal wear thereover, and the lining material 15 at the exterior of the inner coat is against the lining material 12 at the interior of the outer coat.

According to the invention, the inner coat is provided with extra material, preferably along a wedge shaped area arranged symmetrically at the middle of the back from the collar line downward for a length in the order of one foot. It is this extra material which accommodates vigorous arm and shoulder movement of the wearer and it is so arranged as normally to lie flat without bulging or lumping preferably in appropriate folds and to be self restoring to flat condition under the weight of the coat after distention under such arm or shoulder movement.

In the specific embodiment shown, the wool type fabric of the inner coat has a wedge shaped cut-out 22, preferably a triangular cut-out, extending symmetrically thereof from the upper border thereof for a distance preferably in the order of one foot, in the preferred embodiment a triangular cut-out coming to an apex 23. This cut-out is filled with an insert 24 desirably of wool or worsted or similar fabric considerably thinner than that of the coat, but considerably thicker than that of the lining. That insert is preferably a triangular piece of height equal to that of the cut-out but of width considerably greater than that of the cut-out to provide the extra material required for accommodating arm and shoulder movement. In a preferred embodiment the triangular insert is folded lengthwise to provide pleats 25, so that said larger insert when so folded will present a shape and area corresponding to that of the cut-out. To form such pleats the insert material is preferably folded inward

laterally along oblique fold lines 26 and then outwardly along upright fold lines 27 which are substantially in abutment as shown along the altitude of the folded triangular insert. The edges of the insert being stitched at 28 to the main fabric 14 at the edges of the cut-out 22, the inverted apex 23 of the insert will have its pleats anchored thereat. The upper or outer ends of the pleats at the border or collar line of the coat are also anchored in place so that they cannot spread at that region. For this purpose the fabric strip 20' of the slide fastener chain 20 is anchored at reinforce fold 29 by stitching along the length of the border of the coat 11 and to the upper edge of the insert 24.

The lining 15 of the inner coat is preferably made with a cut-out 30 identical with and registering with that of the main fabric of the inner coat and into said cut-out is stitched an insert 31 of material identical with that of the lining and of area and pleated form identical with that of the coat fabric insert 24. Said lining insert pleats are anchored at the upper or rim edge by the same means as anchors the upper or rim edge of the pleats of the main insert 24. Said anchoring means is preferably the stitching 32 for the slide fastener chain 20 affixing the upper or wider end both of the coat fabric insert 24 and of the lining insert 31. As shown in the drawings, the upright fold edges 27 and 27' of the abutting pleats of the main insert 24 and the lining insert 31 respectively are exposed and the connecting webs 33 and 33' respectively of said pleats are concealed between the inner coat and its lining.

When the combined coat is worn, the inner coat will extend without appreciable slack between the lateral facing lengths of the outer coat and the outer coat will completely conceal from view the pleated inserts of the inner coat and if that outer coat is of square cut tailored type it gives no evidence in its appearance in wear of the pleats in the inner coat. Under vigorous arm and shoulder movement, the inner coat which is snugly fitted to the body will distend at the pleats 25 of the insert and the corresponding pleats of the lining fabric thereof. The pleats have sufficient extra material to permit such distension preferably of the order of six or seven inches transversely of the coat along the shoulder line and almost as much along the pleated insert below the shoulder line. Thus destructive strain on seams and on fabric is obviated, regardless how vigorous the arm and shoulder movement. The fabric of the insert 24 by virtue of its thinness as compared to the main fabric 14 retains the folds of its pleats and the three-ply thickness determined by the infolded pleats 25 superimposed over the connecting inner ply or web 33 conjointly will occupy substantially the thickness of the thicker main fabric 14 of the inner coat, thus avoiding lumping at that region. Upon the wearer coming to rest after such arm or shoulder movement the weight of the coat will cause the pleated inserts 24 and 31 automatically to fall back to normal infolded position so that no disarray occurs and no adjustment is required to restore the coat to properly groomed condition.

As many changes could be made in the above construction, and many apparently widely different embodiments of this invention could be made without departing from the scope of the claims, it is intended that all matter contained in the above description or shown in the accompanying drawings shall be interpreted as illustrative and not in a limiting sense.

Having thus described my invention what I claim as new and desire to secure by Letters Patent of the United States is:

1. A coat member comprising a main fabric of relatively heavy material and a relatively thin lining of lining material, said members being secured together in a unitary structure, each of the main fabric and the lining fabric having a triangular cut-out symmetrically thereof extending downward a distance of the order of a foot from the upper rim, inserts filling the respective cut-outs, the insert of the main fabric being of fabric thinner than said main fabric and thicker than the fabric of the lining, the insert of the lining being of lining fabric, each of said inserts being triangular in shape, of height equal to that of the cut-out, but of width considerably greater than that of the cut-out, each of said inserts having a pair of pleats of depth diverging from the apex to the base of the respective triangular areas with their fold edges substantially in abutment along the mid-section thereof, the inserts in thus folded pleated condition corresponding in area to the respective cut-outs and being stitched in place at the respective cut-outs with the abutting folds of the pleats at the respective exposed sides of the coat, said coat member having binder means along the upper edge thereof anchoring the pleats of both the main and the lining fabric inserts against distention.

2. A double-duty coat of the type comprising an outer coat having an inturned facing along the sides and top thereof and a slide fastener chain extending the entire length of said facing, an inner coat of width equal to the span between the lateral portion of said slide fastener chain and having a complementary slide fastener chain extending along the entire edge thereof for snug but removable connection of the two coats, the main fabric of said inner coat having a triangular cut-out extending from its upper rim downward along the mid-section thereof, and an insert of fabric extending along the inner face of said inner coat, said insert being thinner than said main fabric and of area considerably larger than that of said cut-out, said insert being pleated to define substantially the area of said cut-out, the outer face of said inner coat being of lining material and presenting a cut-out substantially registering with the cut-out in the main fabric of said inner coat, said cut-out having an insert of lining material of substantially the same pleated construction as said inner coat insert, said inner coat having a reinforce associated with the slide fastener chain and extending with said slide fastener chain along and affixed to the upper edge portions of said two inserts and fastening the respective pleats of said inserts together at said upper edge portions.
